UNITED STATES PATENT OFFICE.

CHARLES GILBERT HAWLEY, OF CHICAGO, ILLINOIS, ASSIGNOR TO LOCOMOTIVE FIRE-
BOX COMPANY, OF CHICAGO, ILLINOIS, A CORPORATION OF DELAWARE.

TUBE CONNECTION.

Application filed June 21, 1922. Serial No. 570,038.

Primarily my invention relates to improvements in the so-called Nicholson thermic siphon and the method whereby it is installed in a locomotive firebox. The so-called siphon is a substantially triangular water-steaming wall which occupies a vertical longitudinal position in the firebox. The top of the siphon opens through the crown sheet of the firebox and the siphon, as a whole, is, so to speak, suspended from the crown sheet. At its lower forward end the siphon has a so-called intake neck or tubular portion, which is directly connected with the throat of the boiler, that is, the water space directly in front of the flue sheet or throat sheet of the firebox. Obviously the joints between the upper and lower parts of the siphon and the crown and throat sheets must be steam tight, and yet I find that the whole assembly of parts must be so joined together or related as to admit of a considerable difference of expansion and contraction without injury to the thick metal sheets from which both siphon and firebox are formed.

The object of this invention is to provide a siphoned firebox structure which shall be virtually immune from the effects of expansion and contraction.

My invention will be readily understood on reference to the accompanying drawings, which form part of this specification and in which Fig. 1 is a vertical longitudinal section of a typical locomotive firebox containing a thermic siphon, which is installed in conformity with this present invention. Fig. 2 is a vertical cross-section substantially on the line 2—2 of Fig. 1. Fig. 3 is an enlarged vertical section of the throat portion of the boiler, showing how the neck of the siphon is joined thereto. Figs. 4 and 5 illustrate two other shapes in which the connection may be made as required to suit the same to throat sheets and siphon necks in different angular relation.

Commonly the siphon neck is directly welded to the margins of the opening in the throat or flue sheet of the firebox or in the opening of a diaphragm portion which is inserted in and becomes a part of the throat or flue sheet. Any motion between the siphon and the remainder of the firebox is sure to be localized in that connection, and ultimately either the weld breaks, or, due to constant flexing, the throat sheet is cracked

adjacent to the neck of the siphon. I do not mean to say that this is a frequent occurrence, but rather to imply it must be expected to occur at some time and that the time of its occurrence can never be exactly predicted.

The basis of this present invention resides in the conception that a rigid joint need not be, and, indeed, should not be, employed as the connection between the siphon neck and the throat or flue sheet of the firebox. In accordance with this invention, I substitute a joint which permits of a relative movement between the parts, which, though slight, serves to absorb all expansion and contraction differences, thereby relieving all parts from breaking strains. This I accomplish without resort to nicely machined parts; and, in such manner, that, though an actual slip joint is formed, that joint is always tight and is of great durability. I make a particular point of the fact that this invention is so contrived that it may be constructed and applied by ordinary boiler makers and by methods commonly in that trade and without any fine or accurate assistance from machinists.

As stated, the neck of the siphon is tubular or cylindrical. As will be at once apparent on examination of the drawings, I take advantage of the cylindrical form of the siphon neck to enclose it within a metal sleeve, first interposing a copper ferrule. To be exact, the ferrule is first placed on the neck and the heavy metal sleeve is then heated and shrunk on the ferrule, thus insuring a tight joint. It will be understood that the metal sleeve is of the same, or so nearly the same, material as the throat sheet of the firebox as to permit it to be soundly welded to the throat sheet by the common autogenous welding process. Thus, I contrive a firm and substantially rigid connection between the throat or flue sheet and the metal sleeve, and leave the neck free to move in the sleeve without hindrance except by the ferrule or packing of copper or the like. It will be understood that the sliding movement of the neck in the sleeve is almost imperceptible, but nevertheless must be permitted in some such manner as here described if the ultimate breaking of welds and cracking of sheets is to be avoided. It is also to be understood that the flue or throat sheet is capable of taking up most

of the expansion and contraction movements of the siphon, which latter are admirably and suitably communicated to the throat sheet through the medium of the 5 relatively wide collar or sleeve.

5 The details of the drawings may be briefly referred to as follows: The drawings illustrate a locomotive firebox containing two siphons S. As shown, these open 10 through and hang from the firebox crown sheet 2. The neck S¹ of the siphon, which may be either straight or curved, is preferably of such length as to penetrate the water space or throat 3 of the boiler, passing 15 through an opening in the throat sheet 4 of the firebox. This portion 4 is sometimes referred to as the lower part of the flue sheet. As shown, the throat sheet and flue sheet 5 are preferably made from a single 20 sheet. I have not thought it necessary to illustrate a firebox of the combustion chamber type, as the use of the latter in no wise modifies this invention.

Referring now to Fig. 3, it will be seen 25 that the lower end of the siphon neck S is equipped first with a thin ferrule or sleeve 6, preferably made of copper, and that the heavy metal sleeve 7 directly encloses the lower end of the siphon neck and its ferrule. 30 As before stated, the sleeve 7 is heated and shrunk on the neck of the siphon before the latter is placed in position in the firebox. The throat sheet 4 contains an opening large enough to admit the sleeve 7 and after the 35 siphon is correctly positioned the sleeve and throat sheet are united by an autogenous weld 8. This weld is applied progressively and the heat incident to the welding process is not sufficient to disturb the tightness of the 40 sleeve on the packing or ferrule 6. By preference, I flange the inner end 6' of the ferrule against the end of the siphon neck to prevent the possibility of the blowing out of the ferrule by pressure within the throat or 45 water space 3. It will be obvious to those skilled in the art that this construction forms a slip joint notwithstanding the comparatively rough surfaces of the siphon neck and sleeve, the soft metal ferrule always adjusting 50 itself to the movement of those parts.

When the siphon neck approaches the throat sheet 4^a at an acute angle as illustrated in Fig. 5, the sleeve 7^a is preferably made of such length as to preserve its perpendicularity on the siphon neck, notwithstanding 55 the angular position at which the sleeve 7^a is welded in the throat sheet 4^a. However, if desired, the sleeve may be trimmed or cut to the restrictive form illustrated by the two 60 dotted lines 4^b 4^b.

Fig. 4 illustrates the form of the slidable connection when constructed in a firebox having a so-called straight or vertical throat sheet 4^c, in which case the neck S^c of the 65 siphon is usually sharply bent or curved.

But Fig. 4 is more especially intended to illustrate a modification in the form of the copper ferrule. I have here shown in detail the particular copper ferrule which I prefer to use in all cases. It is made in two parts. 70 That is, instead of a single copper sleeve I employ two sleeves 6^d and 6^e, one within the other. These are formed as a unit and are thus placed on the neck of the siphon and together receive the compressive force of the 75 shrinking collar or sleeve B, and so far as serving as a packing, the two parts of the ferrule may be considered as one. But, in event the siphon neck moves within the sleeve 7^d the two parts of the ferrule will 80 slide one on the other and always maintain a very tight joint.

As a rule, both firebox and siphon are made of steel sheets and the welded-in sleeve 7 is likewise made of firebox steel. This construction, therefore, readily lends itself to the process of autogenous welding, and yet the actual joint between the siphon neck and the throat or flue sheet of the firebox is relieved from direct dependence upon the autogenous weld.

I have not thought it necessary to illustrate that modification of my invention in which the sleeve 7 is flanged and riveted, instead of welded, to the throat sheet. That 95 construction is much less desirable than the form herein shown and has several other disadvantages.

One marked advantage of the present invention is that a siphon may be installed in 100 a firebox with a minimum disturbance of the stay-bolts 9 in the throat of the boiler. This is well shown in Figs. 2 and 3.

The wash-out plug 10 is positioned in the outside throat sheet of the boiler to afford 105 access to the interior of the water-leg 3 and the siphon neck.

As will be apparent to boiler makers, the copper ferrule in each case may be made longer than the heavy metal sleeve, and, if need be, the ferrule may be readily calked from the interior of the firebox. The outer end of the ferrule may be calked through the wash-out plug hole.

Obviously my invention has a certain 115 range of adaptation to fire-boxes and water-walls of other forms than herein shown.

Having thus described my invention, I claim as new and desire to secure by Letters Patent:

1. In combination with a fire box sheet having an opening therein, a tubular member having an end extending therethrough, a ferrule of relatively soft metal snugly fitting upon said end of said tubular member, and a heavy, relatively hard metal ring embracing said ferrule and lodged thereon and rigidly attached in said opening in said fire box sheet.

2. In combination with a fire box sheet 130

having an opening therein, a tubular member having an end extending therethrough, a ferrule of relatively soft metal snugly fitting upon said end of said tubular member, and 5 a heavy, relatively hard ring embracing and shrunk upon said ferrule and rigidly welded in said opening in said fire box sheet.

3. In combination with a fire box sheet having an opening therein, a tubular mem-

ber having an end extending therethrough, 10 a ferrule comprising a plurality of relatively soft metal superimposed sleeves fitting upon said end of said tubular member; and a heavy relatively hard metal ring shrunk upon the ferrule and welded in said opening. 15

In testimony whereof, I affix my signature.

CHARLES GILBERT HAWLEY.
